WILLIAM L. MAUND, OF MILAM, TEXAS.

Letters Patent No. 101,371, dated March 29, 1870.

IMPROVED DOUBLE PINCERS.

The Schedule referred to in these Letters Patent and making part of the same.

To all whom it may concern:

Be it known that I, WILLIAM L. MAUND, of Milam, Sabine county, Texas, have invented a new and useful Tool for Boot and Shoe-Makers, being Double Pincers for closing the shanks of a boot or shoe; and I do hereby declare that the following is a full, clear, and exact description of the construction and operation of the same, reference being had to the annexed drawings making a part of this specification.

The nature of my invention consists in providing a single pair of pincers with double jaws, by which both sides of the shanks of a boot or shoe can be clamped and held at the same time, with a view to an equal and simultaneous strain on each side.

To enable others skilled in the art to make and use my invention, I will proceed to describe its construction and operation.

A A are the handles which, being held under pressure, close the jaws D D D D.

The short joint handles B B work on a pivot or bolt at C, and are connected with A A at the points c c forming the jaws of the pincers.

The rod E passes through the four handles and has on one end the head e and on the other end the screw-thread b.

On this screw works the tap F and the washer G.

What I claim as my invention, and desire to secure by Letters Patent, is—

The pincers, as described, with the parts A A B B D D, the screw E and tap F, and springs I I, all constructed and operating substantially as and for the purpose described:

W. L. MAUND.
